(57) **CLAIM**

The ornamental design for an MP3 sound system, as shown and described.

DESCRIPTION

FIG. 1 is an exploded perspective view of an MP3 sound system, showing my new design;

FIG. 2 is a front elevational view of the invention;

FIG. 3 is a rear elevational view of the invention;

FIG. 4 is a right-side elevational view of the invention, the left-side elevational view being a mirror image thereof;

FIG. 5 is a top plan view of the invention; and,

FIG. 6 is a bottom plan view of the invention.
